WILLIAM C. ROE, OF WHEELING, WEST VIRGINIA.

BUZZER APPARATUS FOR PRODUCING WHISTLE-SIMULATING SOUNDS.

1,303,117.

Specification of Letters Patent.

Patented May 6, 1919.

Application filed September 28, 1917. Serial No. 193,701.

To all whom it may concern:

Be it known that I, WILLIAM C. ROE, a citizen of the United States of America, and resident of Wheeling, county of Ohio, 5 and State of West Virginia, have invented certain new and useful Improvements in Buzzer Apparatus for Producing Whistle-Simulating Sounds, of which the following is a specification.

This invention relates broadly to toy railways, and more particularly to apparatus associated with such a railway for producing whistle-simulating sounds.

The primary object of the invention is 15 to provide, in association with a toy railway and a train or locomotive for traveling thereon, an electrically operated device or mechanism whereby a shrill sound approximating the blast of a whistle sound is emitted when such train or locomotive travels 20 over a point or points in the track.

In describing the invention in detail, reference is herein had to the accompanying drawings, in which—

25 Figure 1 is a plan view of a portion of railway track and a locomotive equipped with the invention;

Fig. 2 is a side elevation of the same, a portion of one track rail being shown broken 30 away to illustrate the electrical contact located in the trackway; and—

Fig. 3 is a diagrammatic view of the invention.

Referring to said drawings, in which 35 like designating characters distinguish like parts throughout the several views—

1 and 2 indicate the opposite track rails of a railway mounted upon metallic cross-ties 3 and 3^a and insulated from each other 40 as will hereinafter be described. Mounted to travel upon said track rails is a train or locomotive, as 4, which carries thereon a high frequency electric buzzer consisting of a metallic core member 5, a diaphragm 45 19 carried by the frame members 5^a of said core member in operative relation to the end of a core proper 5^b, and a screw contact 6 mounted to coöperate with said diaphragm, said contact being adjustably 50 carried by a suitable supporting arm or bracket, as 7, mounted upon said core member 5, suitable insulation, as 8, being provided between said contact 6 and its support 7.

55 A coil 9 wound upon the core proper 5^b

has one end grounded upon the core 5, as shown at 9^a. Leading from the opposite end of said coil to a brush 10 carried by the locomotive 4 is a conductor 11, said brush being located in a position to make wiping 60 contact with a metallic contact member or strip 12 located between the track rails 1 and 2 of the railway at an appropriate point.

A conductor 13 leads from the adjustable 65 screw contact 6 to a wheel 14 of the locomotive traveling upon the track rail 1.

A source of current, as a battery 15, has one side connected by a conductor 16 to one of the crossties 3, which latter are insulated 70 only from track rail 2, as shown at 17. The opposite side of the current source is connected by a conductor 18 to a crosstie 3^a which is insulated only from track rail 1, as shown at 24. The contact strip 12 is disposed longitudinally of the railway and is mounted with one end supported upon and insulated from a crosstie 3 and its opposite end seated upon and uninsulated from the crosstie 3^a, current being permitted to pass 80 to said strip from the last-mentioned crosstie. The said contact member or strip consists of a horizontally disposed strip of metal having its opposite ends 12^a downturned to seat upon the crossties 3 and 3^a, 85 as aforesaid, thereby to support its body portion in an elevated position adapted to be engaged by the brush 10 carried by the locomotive. Said body portion may be continuously horizontal throughout, as when it 90 is desired that a long uninterrupted sound resembling that of a whistle be emitted as the locomotive passes thereover. However, it is preferred that the continuity of the surface of said strip which will be contacted by said brush be interrupted by one or more offset portions 12^b formed by depressing the body of the strip at intervals to a level 95 below that at which said brush is carried, thereby to provide a plurality of separated contact-surfaces 12^c which may be made of any desired length or lengths. As depicted in the drawings, two long and two relatively short contact surfaces 12^c are provided, the same being separated by offset portions 12^b of 100 varying lengths, the purpose being to cause two long and two relatively short whistle-simulating sounds to be emitted by the buzzer as the locomotive passes over said strip, said sounds being separated by inter- 105

110

vals of varying lengths. That end of the strip 12 which rests upon the crosstie 3 is insulated from the latter, as shown at 23.

In practice, when the brush 10 carried by the locomotive engages a contact surface 12^c an electric circuit through the buzzer is completed, said circuit consisting of the source of current or battery 15, conductor 16, crosstie 3, track rail 1, locomotive wheel 14, conductor 18, screw contact 6, diaphragm 19, core member 5, coil 9, conductor 11, brush 10, contact strip 12, crosstie 3^a and conductor 18. The closing of the circuit actuates the diaphragm 19 to vibrate against the screw contact 6 which is adjusted to a position for producing a vibration of high frequency, thus causing to be emitted a shrill buzzing sound approximating the blast of a whistle.

20 The wheel 20 of the locomotive opposite the wheel 14 is insulated from its axle 21, as indicated at 22, to prevent the formation of a short circuit.

As is apparent, the polarity may be reversed by reversing the positions of the conductors 16 and 18 leading from the current source.

It will be noted that the arrangement of the wiring connections and the insulation 30 herein shown and described is merely illustrative of a preferred arrangement, it being obvious that other methods of wiring and insulation might be readily employed for accomplishing the result herein aimed at.

35 What is claimed is—

1. A toy railway device for producing audible whistle-simulating sounds, comprising, in combination with a railway and a locomotive traveling thereon, a contact strip 40 located in the line of said railway, a source of electric current connected to said strip, a high frequency buzzer carried by the locomotive and including a metal core, a coil carried by said core, a diaphragm, and an 45 adjustable point contact coöperating with said diaphragm, a brush carried by the loco-

motive for making wiping contact with said contact strip, said brush having connection with said coil, and current-conducting means between said point contact and said current source. 50

2. In a toy railway, apparatus for producing an audible whistle-simulating sound, comprising, in combination with a vehicle for traveling along such railway, a high 55 frequency buzzer carried by the vehicle, a brush carried by said vehicle and connected with said buzzer, a metallic contact strip located along the line of said railway and adapted to be contacted by said brush, said strip having a plurality of separated contact surfaces thereon, a current source connected to said strip, and means including a rail of said railway and a wheel of said vehicle between said current source and said 60 buzzer for completing a buzzer-actuating electric circuit.

3. In a toy railway, apparatus for producing an audible whistle-simulating sound, comprising, in combination with a vehicle 70 for traveling along such railway, a high frequency buzzer carried by the vehicle, a brush carried by said vehicle and connected with said buzzer, a metallic contact strip located along the line of said railway and adapted 75 to be contacted by said brush, said strip having its continuity interrupted by one or more offset portions whereby is produced a plurality of horizontally alined separate contact surfaces, a current source connected 80 to said strip, and means including a rail of said railway and a wheel of said vehicle between said current source and said buzzer for completing a buzzer-actuating electric circuit. 85

In testimony whereof, I affix my signature in presence of two subscribing witnesses.

WILLIAM C. ROE.
